UNITED STATES PATENT OFFICE.

JONAS NORTHRUP, OF HOPEDALE, MASSACHUSETTS, ASSIGNOR TO WILLIAM F. DRAPER, OF HOPEDALE, MASSACHUSETTS; CLARE H. DRAPER AND OLIVER H. LANE EXECUTORS OF SAID WILLIAM F. DRAPER, DECEASED.

SHUTTLE-POSITIONER.

973,128.

Specification of Letters Patent. Patented Oct. 18, 1910.

Application filed September 7, 1909. Serial No. 513,437.

To all whom it may concern:

Be it known that I, JONAS NORTHRUP, a citizen of the United States, residing at Hopedale, in the county of Worcester and 5 State of Massachusetts, have invented an Improvement in Shuttle-Positioners, of which the following description, in connection with the accompanying drawings, is a specification, like letters on the drawings representing 10 ing like parts.

The invention to be hereinafter described relates to looms, and more particularly to the type known as filling replenishing looms.

As well known by those skilled in the art, 15 looms of the above general type are designed to effect replenishment of the filling when that in a shuttle has become exhausted or broken and, in order that the replenishing mechanism may properly discharge its function, 20 it is necessary that the shuttle be properly located in the shuttle-box.

The present invention aims to provide means to insure the correct position of the shuttle preparatory to replenishment, all of 25 which will best be understood from the following description and accompanying drawings of one form or embodiment of the invention, it being understood that in its true scope the invention is not limited to the details illustrated and described but is definitely set forth in the claims.

In the drawings:—Figure 1 is a plan view showing one side portion of a loom containing the present invention, some of the parts 35 being shown in section; Fig. 2 is a section on the line 2—2, Fig. 4; Fig. 3 is a front elevation showing the parts positioned as in Fig. 1, the transferrer and other elements of the filling replenishing mechanism being 40 omitted for clearness of illustration, and other parts being broken away; and Fig. 4 is a view similar to that of Fig. 3 with the parts in another position.

The loom frame, which may be of any 45 usual or desired character suitable to sustain the operating and other parts, is provided with a breast beam 1 to which is secured a bracket 2, Fig. 1, by means of suitable bolts 3, said bracket 2 providing sustaining means 50 for some of the elements of any usual or desired character of replenishing mechanism, which as a whole may be identified by A, Fig. 1. In the present illustration the re-

plenishing mechanism comprises the transferrer 4 mounted on a rod 5 sustained, in 55 part at least, by the bracket 2. The transferrer 4 may have suitable end portions 6 and 7 to engage a filling carrier 8 sustained by any suitable means in position to be moved into the shuttle by the transferrer, 60 the construction being such that upon failure of filling either by exhaustion or breakage, a train of mechanism will be put in 65 operative condition, so that upon a beat up movement of the lay the transferrer will 70 act to transfer a filling carrier from a source of supply into the shuttle, provided the shuttle is properly positioned to receive it, and discharge the carrier previously in the shuttle. This action of the replenishing 75 mechanism and the general construction suitable thereto are well understood by those skilled in the art and consequently need no further elucidation, it being understood that so far as the present invention is concerned 80 any usual or desired form of replenishing mechanism may be employed, the form shown being merely typical.

Since the filling carrier to be transferred to the shuttle occupies a definite position 85 with respect to the length of the shuttle box, it follows that the shuttle to which such carrier is to be transferred should be definitely and properly positioned in its box at the moment of transfer. For reasons well 90 known to those skilled in the art, the shuttle will not always take such definite position. It may sometimes fail to sufficiently enter the box, and under other conditions may enter the box and rebound. In either case, 95 however, regardless of the cause, the shuttle will not be in proper position to receive the fresh filling carrier, with the result that the transfer will not be properly made.

With the above matters in view the features of the present invention will be described in connection with the illustrated form of the invention, which, regardless of structural details, is designed to cause the shuttle to be properly positioned in the box 100 for the action of the transferrer and then free the shuttle previous to the picking movement, so that its path across the lay may be unobstructed.

Mounted in suitable bearings 9 secured to 105 the loom frame, Fig. 1, is the transverse rod

10 of usual character to which is secured the finger 11, said rod 10 being normally under the influence of a spring 12, Fig. 1, one end 13 of which is secured to a fixed part 5 of the loom frame and the other end 14 of which overlies a controller 15 secured by a set screw 16 to said transverse rod, the construction being such that the spring 12 normally holds the rod in position with the 10 finger 11 depressed. When the filling fails for any reason, the transverse rod 10 is turned contraclockwise, looking from the right, Fig. 1, by the usual indicating mechanism, well understood by those skilled in 15 the art and consequently unnecessary to describe, with the result that the finger 11 is raised for a purpose that will presently appear.

The shuttle box 17 may be of usual construction, having preferably an open bottom for the passage of filling carriers discharged from the shuttle and a binder 18, or it may be variously modified.

Projecting from the lay beam 18* is a lug 25 19 which, if desired, may be formed as a part of a plate or bracket 20, Figs. 3 and 4, secured to said beam. Extending from said lug 19 is a supporting stud 21 having mounted on the lower portion thereof the 30 gate or arm 22, which is normally under the influence of a spring 23, one end of which, Fig. 1, is secured to a part 24 fixed to the lay beam and the other end 25 to the gate or arm 22, the construction being such that the 35 spring 23 normally maintains the gate or arm 22 in the position indicated in Figs. 1 and 3 with said gate or arm extending across the passage between the stud 21 and the downwardly extending arm 26.

40 As indicated in Figs. 1 and 3, the gate or arm 22 is formed with an extended portion 27 to which is jointed at 28 one end of a link 29, Figs. 1, 3 and 4, the other end of said link being connected with a shuttle positioner 31.

Extending below the shuttle box is a bracket 32 having the angularly disposed slots 33 and 34 in which move the pins 30 and 35 secured to the positioner 31. In the 50 present form of the invention the slot 33 is shown as straight and substantially vertical and the slot 34 is curved, but it will be understood that variations may be made in these respects, the construction being such that upon movement of the gate or arm 22 about its axis, the shuttle positioner may be actuated to engage the shuttle and then have its shuttle engaging portion travel in the path of shuttle movement, and as the gate or 55 arm 22 returns to normal position the shuttle positioner may move to its initial position with the shuttle engaging portion out of the path of the shuttle movement.

The slot 34 in the present form of the invention has an end portion 36 forming a de-

pressed seat for the pin 30 of the shuttle positioner, so that when the positioner is in normal position, as indicated in Fig. 3, the shuttle engaging portion 37 thereof will be below the path of movement of the shuttle, 70 but when the shuttle positioner is moved in order to position a shuttle in the box, the initial action of the positioner will cause the shuttle engaging end 37 to rise into a recess in the shuttle, preferably the shuttle chamber, and engage the wall thereof, and continued movement of the positioner will cause the end 37 to travel in the path of shuttle movement; and when the positioner returns to initial position prior to the picking movement, the shuttle engaging portion 37 will be positively moved out of the path of the shuttle.

As indicated in Fig. 2, the shuttle positioner is shown as extending upward and 85 when this form or disposition of parts is employed the upper portion of the shuttle positioner is inclined, as indicated, to permit the ready discharge of the ejected filling carrier, though obviously this would not be 90 necessary if the positioner were disposed above the shuttle box.

As hereinbefore noted, the shuttle engaging end of the shuttle positioner may engage the end wall of the shuttle chamber, 95 thus obviating any special construction of shuttle. In the present illustration the shuttle S, which may be of the usual construction employed in filling replenishing looms or otherwise, has the end wall 38 of 100 the usual shuttle chamber 40 provided with a wear piece 39 adapted to be engaged by the upper portion of the shuttle positioner, though this may be omitted if desired. Obviously also the pins 30 and 35 which travel 105 in the slots of the bracket 32 may be provided with rolls or rotary sleeves to decrease wear and frictional resistance.

The picker 41, the picker stick 42 and cushion 43 may be of usual or of any preferred character.

From the construction described and its various modified forms which may suggest themselves to those skilled in the art, it will be seen that under normal working conditions of the loom the finger 11 will remain depressed, so that as the lay beats up it will be below the path of movement of the gate or arm 22 which will maintain its normal position, as indicated in Fig. 1, and hold 115 the shuttle positioner in its initial position. Should the filling break or become exhausted, the transverse rod 10 will be turned by the usual indicating mechanism and raise the finger 11 into the path of movement of the gate or arm 22, and the replenishing mechanism will likewise be set for making the transfer, as already described and as well understood by those skilled in the art. Under these conditions as the lay 125

moves forward, the end of the finger 11 enters between the part 26 and the stud 21, contacts with and turns the gate or arm 22, which, as the lay continues to move forward, actuates the positioner 31, causing its end 37 to rise into the shuttle chamber, and, in case the shuttle is not properly located in its box, to engage the end wall of the chamber and move the shuttle into proper position. It will be noted also that owing to the characteristics and action of the shuttle positioner, the shuttle will be engaged and moved by the positioner even though the shuttle has only slightly entered the shuttle box or has rebounded to an extent that might cause injury to the warp in case the usual protector mechanism failed to act. As the lay reaches front position, and prior to the action of the transerrer, the shuttle positioner will have properly positioned the shuttle for the reception of the fresh supply of filling, and as the lay goes back the positioner will be moved to initial position with its end out of the path of shuttle movement prior to the picking action.

Having reference to Fig. 1, it will be noted that the binder 18 has bearing thereagainst the usual binder finger 50 which controls the position of the dagger 51, Figs. 30 1 and 3, the construction being such that should the shuttle fail to enter the shuttle box sufficiently far to actuate the binder, or should it rebound to a position such that the binder is not moved back by the shuttle, 35 then the binder finger 50 will fail to lift the dagger and the loom will knock off as the lay moves up, in a manner well understood by those familiar with the art. It sometimes happens, however, that the shuttle 40 comes to rest at the end of its pick in such position that it may have moved the binder sufficiently to prevent loom stoppage, and yet be so far out of the box that the shuttle positioning devices heretofore employed fail 45 to discharge their shuttle positioning function, in which case, should the filling replenishing means operate, damage is liable to occur. The present invention, however, obviates this objectionable condition and provides means whereby, should the shuttle enter 50 the box far enough to actuate the binder and prevent the loom "knocking off," the shuttle will be moved into proper position for the action of the replenishing mechanism, and should the shuttle not enter the box sufficiently to actuate the binder then the loom will knock off and stop.

The features of the present invention may be modified in various ways, but applicant 60 believes himself to be the first to provide a shuttle positioner operating in the manner described in a filling replenishing loom, and desires to embrace by the following claims this broad feature which enables proper positioning of the shuttle even though the

shuttle may vary between wide limits in its failure to enter the shuttle box or in its rebound therefrom.

What is claimed is:

1. In a filling replenishing loom, the combination of a lay having a shuttle box, filling replenishing mechanism for replenishing the filling, a shuttle positioner, and means for causing the positioner to enter the bobbin chamber of the shuttle and engage a wall thereof to position a shuttle in the shuttle box. 70

2. In a filling replenishing loom, the combination of a lay having a shuttle box, filling replenishing mechanism for replenishing the filling, a shuttle positioner, and means for causing the shuttle positioner to enter the bobbin chamber of the shuttle and then move in the path of shuttle movement to position a shuttle in the shuttle box. 80

3. In a filling replenishing loom, the combination of a lay having a shuttle box, filling replenishing mechanism for replenishing the filling, a shuttle positioner disposed below the shuttle box, and means for causing the positioner to enter the bobbin chamber of the shuttle and engage a wall thereof to position a shuttle in the shuttle box. 90

4. In a loom, the combination of a lay and shuttle box, a shuttle positioner, and means for causing the shuttle positioner to enter the bobbin chamber of the shuttle, as the lay moves forward, and position the shuttle in the shuttle box. 95

5. In a loom, the combination of a lay, a shuttle box having an opening for the discharge of a filling carrier, shuttle picking means, a shuttle positioner independent of the picking means, and means for causing the shuttle positioner to travel in said opening to position a shuttle in the shuttle box. 100

6. In a loom, the combination of a lay, a shuttle box having an opening for the discharge of a filling carrier, a shuttle positioner, and means for causing the shuttle positioner to enter the bobbin chamber of the shuttle through said opening to engage and position a shuttle in the shuttle box. 110

7. In a filling replenishing loom, the combination of a lay, a shuttle box having an opening for the discharge of a filling carrier therethrough, filling replenishing mechanism, a shuttle positioner, and means for causing the shuttle positioner to enter the bobbin chamber of the shuttle and position the shuttle in the shuttle box. 115

8. In a loom, the combination of a lay and shuttle box, a shuttle positioner, and means for causing the shuttle positioner to enter the bobbin chamber of the shuttle and position the shuttle in the shuttle box and then move out of the path of the shuttle prior to the picking movement. 125

9. In a loom, the combination of a lay and shuttle box, a shuttle positioner, and 130

means for causing the shuttle positioner to enter the bobbin chamber of the shuttle and position the shuttle in the shuttle box and then move back to initial position with the shuttle positioner out of the path of the shuttle prior to the picking movement.

10. In a loom, the combination of a lay, a shuttle box, a swinging shuttle positioner, and means for causing the end of the positioner to enter the bobbin chamber of the shuttle and move an improperly positioned shuttle into proper position in the shuttle box.

11. In a loom, the combination of a lay, a shuttle box, a swinging shuttle positioner, and means for causing the end of the positioner to enter the bobbin chamber of the shuttle and then move in the direction of shuttle movement to engage and move an improperly positioned shuttle into proper position in the shuttle box.

12. In a loom, the combination of a lay and shuttle box, a shuttle positioner, and means for moving the shuttle engaging portion of said positioner into the bobbin chamber of the shuttle and then moving said portion in a substantially straight line to position a shuttle in the shuttle box.

13. In a loom, the combination of a lay and shuttle box, a shuttle positioner disposed below the shuttle box, and means for moving the shuttle engaging portion of said positioner upward into the path of shuttle movement and then moving said portion in a substantially straight line to position a shuttle in the shuttle box and returning the positioner to initial position with the shuttle engaging portion out of the path of shuttle movement prior to the picking action.

14. In a loom, the combination of a lay, a shuttle box, a positioner for engaging and moving an improperly positioned shuttle, a swinging gate, means for swinging said gate, connections between the swinging gate and positioner, and means for directing the positioner to cause its shuttle engaging portion to move into the path of the shuttle and then in a straight line to position the shuttle in the shuttle box.

15. In a loom, the combination of filling replenishing means, a lay, a shuttle box having an opening for the discharge of filling carriers from the shuttle, and a shuttle positioner movable in said discharge open-

ing and comprising a swinging part having a shifting fulcrum and means for moving said part to properly locate a shuttle in the shuttle box for the action of the replenishing means.

16. In a loom, a lay, a shuttle box, a shuttle positioner, having movable fulcrum, a gate, connections between the gate and positioner, and means for swinging the gate.

17. In a filling replenishing loom, the combination of a lay, a shuttle box having a binder, a dagger controlled thereby, a shuttle positioner, and means to cause the shuttle positioner to engage and position the shuttle in the shuttle box through all improper positionings of the shuttle which cause binder movement.

18. In a filling replenishing loom, the combination of a lay, a shuttle box having a binder movable by a shuttle, a shuttle positioner, and means to cause the shuttle positioner to engage and move a shuttle when the shuttle comes to rest in any improper position within the range of binder action.

19. In a filling replenishing loom, the combination of a lay, a shuttle box, a shuttle positioner, and means to cause the shuttle positioner to engage an improperly positioned shuttle from below and move it to proper position in the shuttle box.

20. In a filling replenishing loom, the combination of a lay, a shuttle box, a shuttle positioner having a shifting fulcrum, and means to cause the shuttle positioner to engage an improperly positioned shuttle from below and move it to proper position in the shuttle box.

21. In a filling replenishing loom, the combination of a lay, a shuttle box having an opening for the discharge of filling carriers from the shuttle when in the box, a shuttle positioner disposed below the shuttle box, and means acting only on indication for filling replenishment to move the shuttle positioner in said opening toward the outer end of the shuttle box to engage and move a shuttle in the shuttle box toward the outer end thereof.

In testimony whereof, I have signed my name to this specification, in the presence of two subscribing witnesses.
